UNITED STATES PATENT OFFICE.

WILLIAM HENRY HARRIS, OF LAURIUM, MICHIGAN.

CALIPERS.

1,388,705.

Specification of Letters Patent. Patented Aug. 23, 1921.

Application filed February 18, 1921. Serial No. 446,021.

To all whom it may concern:

Be it known that I, WILLIAM H. HARRIS, a citizen of the United States, and a resident of Laurium, in the county of Houghton 5 and State of Michigan, have invented new and Improved Calipers, of which the following is a full, clear, and exact description.

The present invention relates to new and useful improvements in calipers and the 10 same in an improvement over United States Letters Patent No. 970,817, granted to me September 20, 1910.

It is the primary object of the present invention to provide a caliper in which the 15 legs thereof are automatically maintained in contact with the work by mechanical means instead of depending upon the gripping action of the hand of the operator as is the common practice.

20 It is a further object of the invention to so construct a mechanism of this character that it is especially adapted to the caliper shown and described in my previous patent above mentioned.

25 With the above and other objects in view, reference is had to the accompanying drawings, in which—

Figure 1 is a view in elevation of a pair of calipers constructed in accordance with the 30 present invention;

Fig. 2 is a detail sectional view of a portion thereof;

Fig. 3 is a horizontal sectional view taken on the line 3—3 of Fig. 1.

35 Referring more particularly to the drawings, the reference character 10 designates the legs of the caliper and said legs are of the usual curved form and taper to their free extremities. These legs have their corresponding ends secured together by means of a crown piece 11, in which the legs are pivotally mounted as indicated by the reference character 12. The crown piece 11 is provided with a centrally disposed opening 13,

40 and rigidly secured in said opening in any desired manner is a centering rod 14, the upper end of which is provided with a suitable operating member in the form of a knob 15. This centering rod 14 is provided at its lower end with a bore 16 and mounted in said bore is a pointed member 17, the lower end of which is provided with a point 18, it being understood that the pointed member 17 projects beyond the end of the centering 45 rod 14. This pointed member 17 is cut out as indicated by the reference character 19,

and carried by the centering rod 14 and engaging the cut-out portion 19 of the pointed member 17 is a threaded bolt or the like 20, which bolt serves the purpose of limiting 60 the sliding movement of the pointed member 17 within the rod 14. The reference character 21 designates a coil spring which is positioned in the bore 16 of the centering rod 14 and tends to project the pointed member 65 forwardly at all times by reason of its engagement with the rear end thereof as indicated by the reference character 21'.

Mounted upon the centering rod 14 is a sliding block 22 and said block 22 is provided 70 with extensions 23 in the form of sleeves, said block being provided with a central opening 24 through which the centering rod 14 slides. At opposite sides of the block 22, ears 25 are provided and pivotally secured 75 in openings 26 in said ears as by means of rivets or the like 27, are links 28, said links being pivotally connected to their respective legs 10 of the caliper by means of bolts or rivets 29.

80 Interposed between the crown piece 11 and the upper sleeve 23 of the sliding block 22, is a coil spring 30, adapted to be placed under compression when it is positioned on the centering rod 14. By this construction it 85 will be seen that the helical spring 30 exerts a constant force in a direction to move the sliding block 22 longitudinally of the centering rod 14, and through the medium of the links 28, normally tend to pull the 90 free extremities 35 of the legs 10 toward each other. By this mechanism it is apparent that the free ends 35 of the legs 10 are at all times maintained in engagement with the work by means of the spring 30 instead of gripping the device to move the free 95 ends 35 of the legs 10 into contact with the work as is the common practice.

When it is desired to determine the center 100 of a body, the caliper is passed across the end of the body with the extremities of the legs engaging the sides of the body, the spring 30 serving to maintain the extremities of the legs in contact with the sides of the body. With the parts in this position, the 105 point 18 passes across the end face of the body to make a mark, the point 18 serving to scratch the body. The operation is then repeated by making a mark at an angle to the former point so that a second line is formed 110 which intersects the first-mentioned line. The intersection of these two lines consti-

tutes the center of the end face of the body. It will be understood that owing to the resilient mounting of the jointed member 17, the latter adjusts itself to the face, the center 5 of which is being determined.

I claim:

1. A device of the class described comprising legs, a member pivotally connected to said legs, a centering rod rigidly secured to 10 said member, a slide movably mounted on said rod, links operatively connecting said slide with said legs, and a helical spring interposed between said slide and the member to which the legs are pivotally connected.
- 15 2. A device of the class described comprising legs, a crown piece pivotally connected to said legs, a centering rod carried by the crown piece, a sliding block movably mounted upon said centering rod, means for pivotally connecting the legs to the sliding

block, and a helical spring surrounding the centering rod and interposed between the crown piece and the sliding block whereby the sliding block is moved automatically longitudinally of the centering rod to cause 25 an automatic contraction of the legs.

3. A device of the class described comprising a crown piece, a pair of legs pivotally carried by the crown piece, a centering rod rigidly carried by the crown piece and projecting between said legs, a sliding block carried by the centering rod, a helical spring surrounding the centering rod and interposed between the crown pieces and the sliding block to move the sliding block longitudinally of the centering rod, and means 30 for causing a contraction of the legs upon sliding movement of the sliding block under the influence of said coil spring.

WILLIAM HENRY HARRIS.
